COMBINED HANDLE AND MIXING VALVE FOR FOUNTAIN BRUSHES OR THE LIKE

Millard Fillmore Harty, Jr., Mount Clemens, Mich., as-
signor to Laitner Brush Company, Detroit, Mich., a
corporation of Michigan

Filed Dec. 28, 1959, Ser. No. 58,819

Term of patent 7 years

(Cl. D91—3)

Fig. 1 is a perspective view of a combined handle and mixing valve for fountain brushes or the like showing my new design, with a brush and fragmentary portion of a hose shown in broken lines for illustrative purposes only.

Fig. 2 is an enlarged side elevational view thereof.

Fig. 3 is a top plan view thereof as shown in Fig. 2; and Fig. 4 is an elevational view thereof as seen from the left of Fig. 2.

The dominant features of my design reside in the portions shown in full lines.

I claim:

The ornamental design for a combined handle and mixing valve for fountain brushes or the like, substantially as shown and described.
